UNITED STATES PATENT OFFICE.

ISAAC W. BRAGG, OF ST. JOSEPH, MISSOURI.

BELL-RINGER.

SPECIFICATION forming part of Letters Patent No. 737,329, dated August 25, 1903.

Application filed April 3, 1903. Serial No. 150,889. (No model.)

To all whom it may concern:

Be it known that I, ISAAC W. BRAGG, a citizen of the United States, residing in St. Joseph, in the county of Buchanan and State of Missouri, have invented certain new and useful Improvements in Bell-Ringers, of which the following is a full, clear, and exact description, reference being had to the accompanying drawings, forming part of this specification.

My invention relates to an attachment to locomotives to ring the bell by means of compressed air.

My invention consists in features of novelty hereinafter fully described, and pointed out in the claim.

Figure I is a perspective view of my improved attachment. Fig. II is a vertical longitudinal section. Fig. III is a horizontal section taken on line III III, Fig. II. Fig. IV is a horizontal section taken on line IV IV, Fig. III. Fig. V is a detail vertical section showing the action of the cylinder and valve. Fig. VI is a horizontal section of the cylinder, taken on line VI VI, Fig. II. Fig. VII is a perspective view of the valve.

Referring to the drawings, 1 represents one of the standards that support the bell 2.

3 is a bracket, between the upwardly-extending arms 4 of which is supported a horizontal valve 5, the valve being held at one end by a set-screw 6, (see Fig. III,) that passes through the outer arm of the bracket, and at the other end by having its cone-shaped end 7 fitted in a socket formed in the inner arm of the bracket. The valve has a live-air port 8, that communicates with an air-pipe 9 through a bore 10 in the valve, and an opening 11, formed in the inner arm of the bracket, to which the pipe 9 is connected.

The valve 5 has exhaust-ports 12, one on either side of the port 8.

Mounted on the valve 5 is an upright cylinder 13, that is free to rock on the valve. The cylinder has a bore 14 to receive the valve, and a port 15 leads from the bore to the body of the cylinder, in which fits a piston 16, having a stem 17, that extends out through the end 18 of the cylinder and bears against the wrist-pin 19 of the crank 20 of the bell, into line with which it is held by a yoke 21, projecting from the end 18 of the

cylinder and straddling the wrist-pin 19. On the back of the valve 5 is a stop-pin or finger 22, that is adapted to come against set-screws 23, fitted in ears 24 on the outer arm 4 of the bracket.

The operation of the device is as follows: The bell being started in motion, air is turned on through the pipe 9 and enters the cylinder through the valve 5, thereby causing the piston 16 to exert its force on the bell-crank and causing the bell to be swung in both directions, the cylinder swinging out of a vertical line, as shown by dotted lines in Fig. II. When the finger 22 comes against one of the stops 23, the movement of the valve is stopped and the continued movement of the cylinder causes the port 15 to be brought opposite one of the exhaust-ports 12, when the air will escape from beneath the piston 16, which will fall by gravity (assisted, possibly, by the back swing of the crank 20 when the momentum of the bell is exhausted and it makes its return swing) to the bottom of the cylinder. As the bell swings to the other side of a vertical line the cylinder does also, carrying the valve with it until the finger 22 comes against the other stop 23. The rotary movement of the valve will then cease, and as the cylinder continues to turn the port 15 will be brought opposite the port 8 again and air will enter the cylinder to throw the piston outwardly and give impetus to the bell. The further movement of the cylinder brings the port 15 opposite the other exhaust-port 12, into registry with which it will remain until the bell swings to the other side again and the finger 22 is brought into contact again with the first stop. By thus having the valve rock with the cylinder I get a long exhaust each time, so that the air will have plenty of opportunity to escape from beneath the piston and never check the return swing of the bell.

I do not claim to be the first to mount the cylinder of a bell-ringer so that it will oscillate on a trunnion which acts as a valve; but I believe that I am the first to provide a construction wherein the trunnion, acting as a valve, has a free motion controlled by suitable stops, so that on the return motion of the bell the cylinder will carry the valve with it until the bell has practically reached its

vertical position, thus keeping the exhaust ports open and offering the least possible resistance to the return motion of the bell.

I claim as my invention—

- 5 In a bell-ringer, the combination of a cylinder and valve adapted to swing together, the former having a piston and means to cause it to swing with the bell and the latter having inlet and exhaust ports and being

provided with means for stopping it when it ¹⁰ has moved a distance in each direction with the cylinder, substantially as and for the purpose set forth.

ISAAC W. BRAGG.

In presence of—

C. W. DEAN,
J. R. FARRELL.
